UNITED STATES PATENT OFFICE.

CHARLES D. LANNING, OF DORCHESTER, MASSACHUSETTS.

REPEATER.

1,154,574.

Specification of Letters Patent. Patented Sept. 31, 1915.

Application filed December 13, 1905. Serial No. 291,531.

To all whom it may concern:

Be it known that I, CHARLES D. LANNING, a citizen of the United States, residing at Dorchester, in the county of Suffolk and State of Massachusetts, have invented an Improvement in Repeaters, of which the following description, in connection with the accompanying drawings, is a specification, like letters on the drawings representing like parts.

My invention relates to telephone repeating means, and particularly to repeating means employed for reinforcing the repeated currents.

Telephone repeaters ordinarily employ a receiving magnet connected to be energized by the variable current energy of the initial or transmitting circuit, a variable resistance medium in operative relation to the repeating circuit, and a magnetic connection between the variable resistance and the receiving magnet, so that the variations in the line energy of the transmitting circuit are magnetically transmitted to the resistance and thereby impressed upon the distant listening circuit and usually with increased force. The variable resistance employed is usually some form of microphonic contact comprising a vibratory electrode so positioned with reference to a second electrode, either with or without intervening granular conducting material, that its vibratory movement serves to vary more or less the conductivity of the microphone. The magnetic connection ordinarily comprises an armature working in the field of the receiving magnet, so connected to the vibratory electrode as to cause movement thereof corresponding to the magnetic variations of the receiving magnet. In addition there is also usually employed some factor or element for positioning the vibratory electrode normally with reference to its opposing electrode or electrodes and an element or factor to restore it to or toward its normal position when moved or displaced therefrom by the action of the magnet, which latter vibratory controlling factor may be the same as or other than the positioning factor. For example, the diaphragm attached to the electrode of a "solid back" transmitter, fulcrumed or secured as it is to the walls of the casing, may be said to perform the double function of positioning the electrode and controlling its vibrations, while on the other hand, there might be employed some elastic or other medium

exerting a constant restoring force only upon the vibratory electrode, with additional and separate means for positioning or alining the electrode with reference to the opposing electrode. It has not heretofore been difficult to obtain mere intensification of the repeated currents, but it has been difficult accurately to reproduce the original current undulations harmoniously and without distortion, owing, in large measure, to the disproportionately small amount of energy which the current undulations at the repeating end of the transmitting line represent as compared with the voice energy which produces them at the transmitter. I have found that a successful repeater requires not only a careful and efficient transformation of the line current energy into magnetic energy at the receiving magnet without unnecessary loss, but the direct transmission of the magnet undulations to the vibratory electrode without unnecessary mechanical work and with the elimination of all parts or features which tend to impair an accurate and sensitive response of the electrode to the magnetic variations.

One object of my invention is the provision of repeating means having not only a high magnetic efficiency and a directness of magnetic action upon the electrodes, but an increased responsiveness and sensitivity of the electrode to the magnetic undulations by eliminating the disturbing influences of a mechanical vibration controller or a mechanical positioning element or both.

By my invention I provide means for primarily positioning the vibratory electrode, which means is without the inherent distorting effects of a diaphragm or other mechanical spring, while at the same time acting effectively as a vibratory controller or positioning device for the electrode, such positioning and controlling function in the preferred form of my invention being performed by the constantly acting and invariable force of gravity.

My invention will be best understood by reference to the following description, when taken in connection with the accompanying illustration of one "specific embodiment" thereof, while its scope will be more particularly pointed out in the appended claims.

In the drawings.—Figure 1 is a front elevation of a telephone repeater constructed according to one form of my invention; Fig. 2 is a side elevation of the same; Fig. 3 is

a front elevation and Fig. 4 a side elevation of a modified form; Figs. 5 and 6 are similar views of a third modification; and, Figs. 7 and 8, similar views of a fourth modification.

Referring to the drawings, and particularly to the embodiment of my invention shown in Figs. 1 and 2, the transmitting circuit *a*, indicated conventionally in dotted lines, is connected to the coils of the receiving magnet *b*, the latter being shown as of the permanently magnetized horse-shoe type, commonly employed in commercial telephone receivers. Other forms of magnets may be used, but this simple construction gives an effective magnetic transformation of the current energy. The magnet is preferably so associated with its armature *c* as to provide a substantially complete magnetic circuit, interrupted only at the air gap between the armature and the magnet core, which is necessary to get suitable vibratory movement of the armature. The magnetizing coils are located preferably at the extreme end of the core, so that the armature receives the full effect of all the magnetic flux created by the coils, which latter may be split, or otherwise suitably wound upon their cores. The magnet core shown has the interior filling *d* of babbitt, or other non-magnetic material, and the core is clamped between the non-magnetic blocks *e* and *f*, the latter being vertically adjustable upon the stationary upright guide rods *g*, by means of the delicate screw adjusting device *h*. In order to secure the maximum efficiency of the armature as a part of the metallic magnetic circuit, the same is preferably constructed in block form, that is, with a view to providing a path of suitably low magnetic reluctance to receive substantially the entire magnetic flux from the magnet, as distinguished from a diaphragmatic or other armature, designed primarily for the purposes of flexibility. The armature is preferably in the form of a small, light, rectangular body of soft iron, preferably laminated to eliminate loss through eddy currents and render the same more effective in the energy transformation. The armature is secured to the stud *i*, but insulated therefrom by the collar *k*. The stud *i* is secured to the disk *l* of conducting material, to which is attached the vibratory electrode *m*, the latter being thereby rigidly and directly attached to the armature. The vibratory electrode herein consists of an annular ring of carbon slightly concaved and resting upon the relatively fixed electrode *n*, the latter here comprising an annular carbon ring having an upper surface of greater curvature than the co-operating surface of the vibratory electrode and being secured to the conducting plate *o* in the base *p* of the instrument.

The circuit connections to the vibratory and relatively fixed electrodes of the microphone described, being well understood, are indicated conventionally and in dotted lines only, the connection to the vibratory electrode to the microphone circuit, however, being preferably by means of some light and self-sustained conductor which will offer no substantial resistance to the movement of the electrode. The armature is preferably attached to the vibratory electrode and the latter is arranged for movement in a substantially vertical direction and preferably with its axis of movement coinciding with the line of magnetic pull. 70 75 80 85 90 95 100 105 110 115 120 125

It will be seen that in the described embodiment of my invention the pull of the magnet is opposed wholly by gravity and that the pressure between the electrodes will depend upon the weight of the armature-electrode and the connections diminished by the upward pull of the magnet. When the instrument is initially adjusted the vibratory electrode is given the desired pressure upon or position relative to the fixed electrode by a suitable adjustment or proportioning of the initial field, this acting to exercise a constant upward pull upon the armature-electrode structure. Whether permanently magnetized or not the magnet is preferably given a light initial field, this permitting a reduction of the air gap between the armature and the magnet core. The current undulations passing through the receiving magnet add to or detract from this initial pull tending either to raise the vibratory electrode against the force of gravity or permit a greater proportion of the weight of the vibratory structure to be effective in pressing against the stationary electrode. 90 95 100 105 110 115 120 125

It will be seen that in the action of this armature, not only are the armature and its associated electrode connected rigidly and directly to form a simple composite structure with unity of movement and action, but that the positioning and control of the electrode against the action of the magnet is effected by the constantly acting and unchanging force of gravity leaving the structure unattached to any controlling or positioning agents and free to give unrestricted response to the varying pull of the magnet. This eliminates the distorting effect of an electric medium, like a mechanical spring or diaphragm or of any stationarily attached positioning member, which effect is present, to a greater or less extent where such a device is employed as the principal or primary positioning or controlling agent.

By keeping the armature without the path of the current passing through the microphone, any choking or conflict between the magnetic flux of the receiving magnet and the magnetic flux introduced by the microphone current is avoided. 130

In the embodiment of my invention described the initial contact between the electrodes is enforced by the weight of the armature-electrode structure and regulated by 5 the directly aligned and accumulated initial and variable pull of the magnet. In the modification shown in Figs. 3 and 4 the fixed electrode is inverted and attached to the bottom of the base p' , the vibratory electrode 10 m' being also inverted and connected to the armature by the elongated stud i' passing through the aperture in the base. In this construction the two electrodes are normally drawn toward each other by the initial pull 15 of the magnet which, as before, can be regulated as desired, the initial magnetic pull acting against the force of gravity tending to separate them.

In the form shown in Figs. 3 and 4 where 20 the magnet draws the electrodes into contact the stationary electrode forms an abutment imposing an approximate limit to the attractive pull of the magnet, so that the armature can normally be brought into very close ap- 25 proximation to the magnet poles, thereby greatly increasing the intensity with which the line variations are imposed upon the microphone in the form of varying pressure between the contact electrodes. In this re- 30 spect it is preferable to the form shown in Figs. 1 and 2, where, it being impossible in practice to regulate the initial magnetism of the magnet with nicety and exactness, any attempt to bring the armature too close to 35 the magnet poles may result in lifting the armature into actual contact therewith.

My invention is not limited to any particular microphonic form of contact and in Fig. 5 I have shown its principles applied 40 to a microphone resistance employing a plurality of carbon point electrodes r , attached to a metallic plate l' and working in conjunction with a fixed electrode n' and mass of interposed granular carbon s . The fixed 45 electrode n is provided with a double cylindrical partition wall t , between which is freely movable a similar partition wall u attached to the vibratory plate l' , whereby the loose carbon material is prevented from 50 escaping.

To illustrate a further modification of my invention, in Figs. 7 and 8 there is shown an instrument similar to that shown in Figs. 5 and 6, the vibratory electrode being in the form of a shallow cup-shaped structure carrying the loose carbon and compressing the same between the bottom of the cup and the downwardly directed carbon points which are attached to the fixed electrode.

It will be noticed that, since the rigidly connected armature and vibratory electrode move in a straight line, the movements of the armature in response to the varying pull of the magnet tend to cause no rocking movement whatever of the vibratory elec-

trode relatively to the stationary electrode. It will also be noticed that, in the case of the solid annular form of electrode, the relatively great diameter of the line of electrode contact as compared with the distance 70 between the two magnetic poles brings the lines of magnetic pull within the limits of the annulus of microphonic tact and gives a very extensive and firm seat for the movable electrode so that, if there is a greater 75 pull at one side of the armature than the other, or, for any other reason, the pull is eccentric, the electrode will still be held against rocking and continue to preserve a firm, even contact throughout its entire ex- 80 tent instead of tending to concentrate it at one point and thereby decreasing the efficiency of the apparatus. It will be seen that in the construction shown in Figs. 1 to 4, 85 inclusive, the related electrode surfaces diverge gradually and progressively from the contact line.

In the described embodiment of my invention desired simplicity is obtained, this being effected by the elimination of those 90 mechanical effects which are ordinarily present with attendant distortion.

My invention is not necessarily limited to a construction wherein the pull of the receiving magnet is opposed by gravity, 95 since the latter forces may act in the same direction as the pull of the magnet and other distortionless forces or factors, such, for example, as those developed by the compressibility of the carbon material of the microphone, relied upon to control or position the vibratory electrode. In such a construction, as well as those disclosed, gravity would act as a coördinating force without a distort- 100 ing effect upon the vibration of the electrode, and it is within my invention to employ coördinating forces other than gravity 105 to act with or against the pull of the receiving magnet, the principal object of my invention being the suppression of distorting 110 factors in the construction and operation of the repeater.

While I have described one form of my invention, it is, of course, to be understood that the same is not limited to the construction, form or respective arrangement of parts, either of the mechanical features, the microphonic features, or the armature-electrode structure, but that extensive modifications and variations may be made therein 115 without departing from the spirit of the invention.

Claims:

1. In a telephonic apparatus, a variable resistance medium comprising an annular 125 electrode having an annular convex face and a coöperating annular electrode having an annular concave face of greater curvature.

2. In a telephone apparatus, a receiving 130

5 circuit, a magnet therein, a variable resistance medium comprising an annular electrode having a convex surface and a co-operating annular electrode having a concave surface of greater curvature, the convex and concave surfaces of said electrode bearing one upon the other, an armature in magnetic relation to said magnet and connected with one of said electrodes for varying the pressure contact between them and hence the conductivity thereof.

10 3. In a telephone apparatus, a receiving circuit, a magnet therein, a variable resistance medium comprising a pair of annular electrodes, one having a convex surface bearing against the surface of the other electrode, and an armature in magnetic relation to said magnet and connected with one of said electrodes for varying the pressure contact between them and hence the conductivity thereof.

15 4. In a current varying instrument a fixed annular electrode, a movable annular electrode, one of said electrodes having a convex bearing surface, an armature to said movable electrode, a magnet adapted by its action upon said armature to maintain said electrodes in contact, and means to vary the magnetic pull of said magnet.

20 5. In a current varying instrument a magnet, a movable electrode, a fixed annular electrode between the movable electrode and the magnet, and a magnet connection between the movable electrode and the magnet 25 passing through the said annular electrode.

6. In a current varying instrument, the combination with a multi-polar magnet, of a fixed annular electrode, a movable annular electrode, and an armature connected to said movable electrode, said electrodes having a diameter greater than the distance between the poles of said magnet.

25 7. In a telephone repeater having a receiving circuit, a receiving magnet, a transmitting circuit containing a variable resistance transmitting medium having a movable electrode and a separate armature having a central connection to said electrode, said armature and connected electrode being so far separated as to substantially remove the electrode from the influence of the magnetic field constituting a connection between the magnet and said medium having unrestricted vibratory movement due 30 solely to the pull of the magnet and the weight of the said connection, for the transmission of current variations from the receiving circuit to the transmitting circuit.

35 8. A telephone relay or repeater having an electro-magnet, a microphone and a magnetically suspended armature responsive to magnetic variations for actuating the microphone, all the lines of magnetic pull upon said armature lying within the limits 40 of microphonic contact.

9. A telephone repeater having a receiving circuit, a receiving magnet, a transmitting circuit containing a variable resistance transmitting medium and an armatured electrode connection between said magnet and said medium, said connection having unrestricted vibratory movement due solely to the pull of the magnet and the weight of the said connection for transmitting current variations from said receiving circuit to said transmitting circuit, all the lines of magnetic pull upon the armature lying within the limits of microphonic contact.

45 10. In a telephone relay, in combination, a microphone in series with its transmitting circuit and comprising two solid electrodes shaped to give a linear contact surface symmetrically disposed about a center, the electrode surfaces diverging from the contacting line; a rigid support for one electrode; means to maintain unbroken contact between said electrodes; an armature centrally mounted on the other electrode; and a receiving electro-magnet operatively related to said armature, said armature being subject wholly to the controlling influence of gravity and said electro-magnet and the coil of said electro-magnet being operatively related to the receiving circuit.

50 11. In a telephone relay in combination a microphone in series with a transmitting circuit and comprising two solid electrodes shaped to give a substantially circular linear contact in a plane therebetween and so that the related electrode surfaces diverge gradually and progressively from the contact line; a rigid support for one electrode; an armature centrally attached to the other electrode by means passing centrally through the first electrode; an initially energized magnet arranged to act upon said armature, thereby to maintain said electrodes in unbroken contact; and a receiving coil for said magnet operated by the received voice currents.

55 12. In a telephone relay, in combination, a substantially vertically-positioned downwardly-pointing initially-energized receiving magnet with a winding therefor adapted to be energized by received currents; a microphone horizontally disposed below said magnet with a transmitting circuit and comprising two solid electrodes shaped to give a substantially circular linear contact with diverging contact walls; a rigid mounting for the upper electrode; and an armature for said magnet, concentrically and rigidly arranged on the lower electrode; whereby said electrodes are maintained in unbroken contact by said magnet and said lower electrode is vibrated by the co-action of gravity and the received telephone currents.

60 13. In a telephone relay, in combination, a vertically-positioned downwardly-pointing initially-energized receiving magnet

- with a receiving winding therefor; a horizontally positioned microphone therebelow, in series with a transmitting circuit, and comprising two solid electrodes shaped to give a linear contact surface symmetrically arranged about the central axis of attraction of said magnet; a rigid support for the upper electrode, a block armature in the field of said magnet, a stem connecting the armature centrally to the lower electrode and passing centrally through a free opening in the upper electrode; whereby said electrodes are maintained in unbroken contact by said magnet and telephonically vibrated by the received voice currents and gravity.
14. In a telephone relay, in combination, with an initially magnetized receiving magnet and its armature, the latter operatively covering the pole or poles of said magnet, a microphone comprising two solid electrodes held in unbroken contact by the action of said magnet and formed to give an electrode contact in linear form symmetrically and concentrically arranged about the central axis of magnetic attraction on said armature; the magnet pole or poles lying within the form inclosed by said contact line.
15. In a telephone relay, in combination, a vertically - arranged, downwardly - pointing electro-magnet with its coil in a receiving circuit, a horizontally positioned microphone therebelow comprising solid electrodes formed to give an annular contact in
- horizontal plane between the converging electrode surfaces; a fixed support for the upper electrode; an armature for said magnet and a central rigid connection from said armature to the lower electrode structure; whereby said magnet and gravity action co-act to vibrate said movable electrode; the microphone annular contact diameter being in excess of the related diameter of the magnet pole or poles and the associated armature; and a transmitting circuit in series with said microphone.
16. In combination, a microphone comprising two solid electrodes shaped to cause a linear contact surface therebetween symmetrically disposed about a center, the electrode surfaces gradually and progressively diverging from the contact line, and means to vary the pressure between said electrodes.
17. In combination, a microphone comprising two solid electrodes shaped to cause a linear contact surface therebetween symmetrically disposed in a plane and about a center, the electrode surfaces diverging from the contact line at a progressively increasing angle, and means to vary the pressure between said electrodes at a right angle to the contact plane.
- In testimony whereof, I have signed my name to this specification, in the presence of two subscribing witnesses.
- CHARLES D. LANNING.
